US00D873832S

(12) **United States Design Patent** (10) Patent No.: **US D873,832 S**
(45) Date of Patent: ** Jan. 28, 2020

(54) **DISPLAY FOR AN ELECTRONIC DEVICE**

(71) Applicant: **Apple Inc.**, Cupertino, CA (US)

(72) Inventors: **Jody Akana**, San Francisco, CA (US); **Bartley K. Andre**, Palo Alto, CA (US); **Shota Aoyagi**, San Francisco, CA (US); **Jeremy Bataillou**, San Francisco, CA (US); **Daniel J. Coster**, San Francisco, CA (US); **Daniele De Iuliis**, San Francisco, CA (US); **M. Evans Hankey**, San Francisco, CA (US); **Matthew David Hill**, Santa Clara, CA (US); **Julian Hoenig**, San Francisco, CA (US); **Richard P. Howarth**, San Francisco, CA (US); **Jonathan P. Ive**, San Francisco, CA (US); **Duncan Robert Kerr**, San Francisco, CA (US); **Jared Kole**, San Francisco, CA (US); **Stefan Mag**, San Francisco, CA (US); **Nicholas George LeBreton Merz**, San Francisco, CA (US); **Scott A. Myers**, San Francisco, CA (US); **Benjamin J. Pope**, Sunnyvale, CA (US); **Matthew Rao**, San Francisco, CA (US); **Matthew Dean Rohrbach**, San Francisco, CA (US); **Peter Russell-Clarke**, San Francisco, CA (US); **Mikael Silvanto**, San Francisco, CA (US); **Christopher J. Stringer**, Woodside, CA (US); **Tang Yew Tan**, San Francisco, CA (US); **Eugene Antony Whang**, San Francisco, CA (US); **Rico Zörkendörfer**, San Francisco, CA (US)

(73) Assignee: **Apple Inc.**, Cupertino, CA (US)

(**) Term: **15 Years**

(21) Appl. No.: **29/575,610**

(22) Filed: **Aug. 26, 2016**

Related U.S. Application Data

(63) Continuation of application No. 29/466,601, filed on Sep. 10, 2013, now Pat. No. Des. 765,084.
